UNITED STATES PATENT OFFICE.

STEPHEN ROSSON LESHER AND ROBERT F. LESHER, OF NEW YORK, N. Y., ASSIGNEES
TO LESHER WHITMAN & CO., INC., OF NEW YORK, N. Y., A CORPORATION OF NEW YORK.

DESIGN FOR A TEXTILE FABRIC.

Application filed January 25, 1929. Serial No. 29,782. Term of patent 3½ years.

To all whom it may concern:

Be it known that we, STEPHEN ROSSON LESHER and ROBERT F. LESHER, citizens of the United States, residing at New York city, in the county and State of New York, respectively, have invented a new, original, and ornamental Design for a Textile Fabric, of which the following is a specification, reference being had to the accompanying drawing, forming part thereof.

The figure is a plan view of a textile fabric, showing our new design.

We claim:

The ornamental design for a textile fabric, as shown.

STEPHEN ROSSON LESHER.
ROBERT F. LESHER.
